STEAM IRON

Merrill M. Kistner, Winsted, Conn.

Application October 7, 1948, Serial No. 53,272

4 Claims. (Cl. 38—77)

1

This invention relates to steam irons and more particularly to an improvement in steam irons by means of which the time lag in the production of steam at the beginning of an ironing operation is reduced to a minimum. In my prior Patents Nos. 2,313,382 and 2,384,839, granted on March 9, 1943, and September 18, 1945, respectively, I have disclosed and claimed a steam iron construction in which a water reservoir is mounted over the sole plate and water is delivered from the reservoir through a valved outlet to passages in the sole plate in which it is converted into steam. The outlet is arranged adjacent the nose of the iron and when the user pauses to place an article on the ironing board, or for other reasons, the iron may be placed in an up-ended position on its heel to interrupt the flow of water to the sole plate. This eliminates the necessity of opening and closing the valve each time the ironing operation is interrupted.

While the provision of a reservoir and feed conduit that will interrupt the flow of water to the sole plate when the iron is up-ended is a desirable feature, it has been found, in some instances, to have one disadvantage. As the quantity of water in the reservoir diminishes, there is a lag between the time when the iron is brought back to ironing position and the time when steam is produced. In the ironing of some fabrics, particularly synthetics, this may result in scorching or burning the article being ironed.

In the present invention I provide means whereby the advantages of disconnecting the reservoir from the sole plate when the iron is up-ended are still obtained and the disadvantage avoided. To accomplish this, I provide a plate extending partially across the reservoir. This plate is curved in horizontal cross section and thus forms a cup or chamber when the iron is up-ended which will retain a portion of the water in the reservoir. The plate is arranged adjacent the outlet from the reservoir to the sole plate and the water thus retained in the plate is immediately available for steam supply when the iron is returned to its ironing position.

In addition to serving as an auxiliary reservoir to retain a quantity of water adjacent the conduit when the iron is up-ended, the plate further serves as a baffle to prevent surging when the main quantity of water moves forwardly in the reservoir after the iron is returned to its ironing position. It further serves to prevent surging during the ironing operation when the movement of the iron in one direction is stopped.

In the accompanying drawing I have shown one embodiment of the invention. In this showing:

Fig. 1 is a side elevation of a steam iron, parts being shown in section;

Fig. 2 is a horizontal, sectional view on line 2—2 of Fig. 1;

2

Fig. 3 is a side elevation of the iron in up-ended position;

Fig. 4 is a detailed, sectional view on line 4—4 of Fig. 2; and

Fig. 5 is a perspective view of the baffle or chamber in the reservoir.

Referring to the drawing wherein I have shown a steam iron of the general construction shown in my prior Patent No. 2,384,849 but wherein certain details, not necessary for the understanding of the present invention, have been omitted for clarity, the reference numeral 1 designates generally the sole plate of the iron which is provided with a heating element (not shown), steam passages (not shown) and outlets in its lower or pressing face (not shown) which may be of the construction disclosed in said patent or of similar functioning construction. The iron is also provided with a thermostat which is controlled by a control member 2 and may be provided with suitable connections between the thermostat and the heating element to a plug (not shown) to be connected by suitable wiring to an electrical outlet. Above the sole plate I provide a shell 3 which extends over the upper portion of the sole plate and within this shell I provide a water reservoir 4. A handle 5 is mounted over the shell. The bottom of the reservoir is provided with a valve seat 6 adapted to be engaged by a valve member 7 and the valve member is controlled from a knob 8 extending through the handle and connected to the valve in any suitable way.

The parts heretofore described are of conventional steam iron construction and form no part of the present invention, except in the combination claimed. To prevent delivery of the water through the valve seat 6 to the sole plate, when the iron is in the up-ended position shown in Fig. 3, the reservoir 4 is so shaped that the quantity of water normally present in the reservoir will not extend as far upwardly as the position of the valve seat with the iron in this position. As shown, the front and top of the reservoir is formed by the shell 3. A plate 9 is welded or otherwise secured to the front of the shell and extends rearwardly therefrom to form a relatively long, shallow reservoir. This plate is extended upwardly to form the rear wall 10 of the reservoir and secured to the inside of the shell as at 11. With an iron of such construction when the iron is moved from the up-ended position to the ironing position shown in Fig. 1 of the drawing, particularly after some of the water originally placed in the reservoir has been consumed, the water must flow from a point near the rear wall 10 of the reservoir to the valve seat 6 before it can be delivered to the sole plate. In the present invention I provide a curved wall 12 (see Fig. 2) extending from a point adjacent one side of the reservoir to a point adjacent the

other side of the reservoir and extending from the top to the bottom of the reservoir. This wall is placed immediately behind valve seat 6. It is preferably provided with a top flange 13 and a bottom flange 14 to secure it to the top and bottom of the reservoir. The top flange may be secured to the inside of the top of the shell by welding or in any other suitable manner. The bottom may likewise be secured to the bottom 9 of the reservoir in any suitable manner. I may thus provide two or more openings 15 in the bottom wall of the reservoir and the bottom flange 14 may be punched to provide tabs 16 (see Fig. 4). These tabs may be passed through the openings 15 and then secured to the lower side of the wall 9 by silver solder or in any other suitable manner.

The operation of the device will be apparent from the foregoing description. In ironing, the iron is in the position shown in Fig. 1 of the drawings. When the iron is temporarily not in use, as when the user is removing an article which has been finished from the ironing board and replacing it with another article, the iron is arranged in the position shown in Fig. 3 of the drawing. The rear wall 10 of the reservoir then forms the bottom of it and the water contained in the reservoir is in that portion to the rear of the valve seat 6. However, with the baffle 12 in the position shown, when the iron is moved to the position shown in Fig. 3 of the drawing, a small portion of the water is trapped within this wall which then functions as a cup or container. When the iron is again brought to the ironing position, the water in the cup 12 is a much shorter distance from the opening in the bottom of the reservoir than the main quantity of water which is at the rear of the reservoir. The result is that water is delivered to the sole plate as soon as, or before, the iron has actually assumed an ironing position and steam is available immediately.

As stated, the cup also serves as a baffle to prevent surging. The larger quantity of water which travels to the rear of the reservoir when the iron is placed on end, has a tendency to move toward the front of the reservoir at a high rate of speed as the iron is swung to a horizontal position but in doing so, a considerable quantity of it comes in contact with the wall 12 and its movement is slowed down. Also during the ironing operation when the forward movement of the iron is stopped, there is a tendency toward surging which is substantially reduced by the presence of the baffle 12.

Another feature of the invention to which the plate 12 contributes is the dissipation of heat radiated from the sole plate to the reservoir. When the iron is in operation, it is desirable to keep the temperature of the water in the reservoir as low as possible. By employing the plate 12, which serves, also as a brace, I am able to use thinner gage metal in plates 3 and 9 than would otherwise be possible. This permits freer dissipation of heat than if heavier metal were employed.

In addition, it will be noted that I provide an air space 17 between the top of the sole plate and the bottom of the reservoir. I may further provide a plurality of openings 18 in the shell just beneath the bottom of the reservoir. These openings, on each side of the shell, permit circulation of air and then assist in cooling the reservoir.

I claim:

1. In a steam iron of the flash type having a

sole plate provided with heating means to convert water into steam, a water reservoir over the sole plate, an outlet from the reservoir to deliver water to the sole plate, the outlet being arranged adjacent the nose portion of the iron to interrupt the flow of water to the sole plate when the iron is up-ended on its heel, and a manually operable valve controlling the outlet, the combination of a baffle plate in the reservoir in the rear of and adjacent to the outlet, the baffle plate extending from the top to the bottom and from a point adjacent one side of the reservoir to a point adjacent the other side and being shaped to trap a quantity of water when the iron is up-ended.

2. In a steam iron of the flash type having a sole plate provided with heating means to convert water into steam, a water reservoir over the sole plate, an outlet from the reservoir to deliver water to the sole plate, the outlet being arranged adjacent the nose portion of the iron to interrupt the flow of water to the sole plate when the iron is up-ended on its heel, and a manually operable valve controlling the outlet, the combination of a curved plate in the reservoir in the rear of the outlet, the concaved side of the plate being toward the front and adjacent to said outlet, the baffle plate being spaced from at least one wall of the reservoir to permit flow of water in the reservoir and to trap a quantity of water when the iron is up-ended.

3. In a steam iron of the flash type having a sole plate provided with heating means to convert water into steam, a water reservoir over the sole plate, an outlet from the reservoir to deliver water to the sole plate, the outlet being arranged adjacent the nose portion of the iron to interrupt the flow of water to the sole plate when the iron is up-ended on its heel, a manually operable valve controlling the outlet, the combination of a baffle plate in the reservoir in the rear of the outlet and adjacent to the outlet, the baffle plate being shaped to form a cup having its open end toward the front of the iron to trap a quantity of water when the iron is up-ended and being spaced from at least one wall thereof.

4. In a steam iron of the flash type having a sole plate provided with heating means to convert water into steam, a water reservoir over the sole plate, an outlet from the reservoir to deliver water to the sole plate, the outlet being arranged adjacent the nose portion of the iron to interrupt the flow of water to the sole plate when the iron is up-ended on its heel, and a manually operable valve controlling the outlet, the combination of a member mounted in the reservoir in the rear of and adjacent to the outlet and spaced from at least one wall thereof, said member being shaped to trap a quantity of water when the iron is up-ended on its heel.
